UNITED STATES PATENT OFFICE.

JOHN WOOLDRIDGE, OF CHILDRESS, TEXAS.

BOLL EXTRACTOR.

Application filed June 14, 1926. Serial No. 115,902.

The present invention relates to a machine especially designed for separating and cleaning boll cotton; the primary object of the invention being to provide novel means whereby boll will be subjected to a thorough cleaning so that the lint cotton may be entirely removed from the boll.

An object of the invention is to provide means for knocking the burr onto the feeding brush, should the burr hang to the cotton, to the end that the burr containing the cotton will again be passed to the brushes and saws of the machine.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

25 Figure 1 is a longitudinal sectional view through a machine constructed in accordance with the present invention.

Figure 2 is a sectional view taken on line 2-2 of Figure 1.

30 Figure 3 is a fragmental elevational view of one side of the machine.

Referring to the drawings in detail, the machine includes a housing indicated generally by the reference character 5, in which 35 housing the various brushes, saws and feed rolls are mounted for operation.

At the upper end of the housing 5 is an opening 6 through which the bolls that are treated by the machine, pass, on their entrance to the machine.

The reference character 7 indicates feeding rolls which are geared to rotate slowly in opposite directions, to the end that the material fed into the machine will be passed 45 downwardly to the rotary brush 8 that operates between the rolls 7 and in spaced relation therewith as shown by Figure 1, so that the bolls will be partially broken by their contact with the brush 8.

50 A casing indicated at 9 forms a part of the housing and is formed preferably of wire mesh material to the end that the brushes 10 of the member 8 will further act to break the bolls when they are rubbed 55 against the casing therein. The housing 5 is constructed in such a way that there is

provided an upper compartment 5' and a lower compartment 6', the compartments communicating through the spout 11 to the end that as the material is fed into the machine and carried over the casing 9 by the brush 8, the material will be thrown into the spout 11 and fed to the gin saw supported therein. The reference character 26' indicates a partitioning member dividing the 60 housing into upper and lower compartments.

Operating adjacent to the spout 11 is a feed brush 12 which is designed to carry material to the gin saws 13 which in turn act to remove the lint cotton therefrom. As 70 shown by Figure 1, a roll 14 is provided, the same carrying substantially wide blades 15 that move in proximity to the brush 12, so that should bolls be fed laterally before the cotton is freed therefrom, the blades will 75 catch the bolls and return them to the feed brush 12 to again be treated by the saws operating adjacent thereto.

Operating at the same rate of speed as the feed brush 12 is a spike roll 16 which operates adjacent to the plate 17 to crush the bolls, the plate 17 also cooperating with the gin saws 13 to further crush the bolls. The bolls are removed from the gin saws by means of the brush 18 that contacts with the 85 gin saws, the direction of rotation of the brush 18 being such as to throw the burrs into the discharge spout 19.

Cotton is removed from the gin saws by means of the brush 20 which operates in the 90 casing 21 that in turn is provided with a discharge spout 22.

It might be further stated that adjustable spiked bars 22' are arranged adjacent to the front wall of the machine, the spiked bars 95 22' having arms extending therefrom, which arms are connected by the bar 24' so that the bars 22' may be adjusted simultaneously. A lever 25' is provided for moving the bar 24' to accomplish this adjustment. The spikes 100 thereof cooperating with the spikes of the rolls 16 to break the bolls and due to the construction of the spiked bars 22', it will be seen that the spiked bars may be adjusted for treating bolls of various sizes and in 105 various conditions.

From the foregoing it will be seen that the construction of the rolls and brushes of the machine are such as to thoroughly separate the burrs from the lint cotton, eliminating 110 any possibility of the burrs passing through the machine with the lint cotton and thereby

causing a finer grade of cotton to be removed from the bolls.

I claim:

1. In a machine of the class described, a housing including an upper compartment and a lower compartment, gin saws operating in the lower compartment, a feed brush for feeding material to the gin saws, a spiked roller operating adjacent to the gin saws, a crushing plate disposed between the spiked roller and gin saws and adapted to cooperate with the spiked roller and gin saws to crush bolls passed into the machine, spiked bars cooperating with the spiked roller to break the bolls, and means for adjusting the spiked bars.
2. In a machine of the class described, a housing, a partitioning member within the housing and dividing the housing into communicating upper and lower compartments, gin saws operating adjacent to the partitioning member and disposed within the lower compartment, a roll having a plurality of

substantially wide blades extending therefrom operating adjacent to the gin saws, a plate disposed in spaced relation with the gin saws and against which bolls move in passing through the machine to crush the bolls, and means for cleaning the saws.

3. In a machine of the class described, a housing, a partitioning member within the housing for dividing the housing into communicating upper and lower compartments, gin saws operating in the lower compartment, discharge spouts arranged on opposite sides of the gin saws, means for feeding material to the gin saws, brushes operating at the mouths of the discharge spouts and contacting with the gin saws to remove material from the gin saws, and said brushes adapted to throw material through the discharge spouts.

In testimony that I claim the foregoing as my own, I have hereto affixed my signature.

JOHN WOOLDRIDGE.
